UNITED STATES PATENT OFFICE.

GEORGE W. MOSHER, OF NEWPORT, KENTUCKY.

FLY SCREEN.

Application filed March 29, 1919. Serial No. 285,987.

To all whom it may concern:

Be it known that I, GEORGE W. MOSHER, a citizen of the United States, and a resident of Newport, in the county of Campbell and State of Kentucky, have invented certain new and useful Improvements in Fly Screens, of which the following is a full, clear, and exact description, reference being had to the accompanying drawing, forming part of this specification.

My invention relates to a device for attachment to fly screens which will act as a trap for flies and lead them to walk out of doors, through the trap, from the inside 15 of the screen. The device as shown is applied to a window screen, but it will be understood that it can as well be applied to doors, screened walls or the like.

I accomplish the object of my invention, 20 as above stated, by that certain construction and arrangement of parts to be hereinafter more specifically pointed out and claimed.

In the drawing,

Figure 1 is a perspective view of the outside 25 side of a window with the screen device in place.

Figure 2 is a sectional perspective of one end of the device, showing the outside thereof.

Figure 3 is a like view of an end of the 30 device showing the inside thereof, the construction of the parts being in a different form.

Figure 4 is another modification similarly 35 shown.

One alternative form of my invention (Figure 2) comprises three pieces of metal with the necessary rivets or bolts to hold them together and in place. There are two 40 straight narrow bars 1, 2, and a bent or folded section of metal or like material, having the lower piece A and the upper piece B, same to be mounted on any screen C, said pieces A and B connected to 45 tongues 16.

The lower bent or folded piece A comprises a straight portion 3 which is set against one side of a piece of screen wire, at any point in its length, as opposed to 50 the bar 1 on the other side of the wire. The two pieces are then secured to the wire by means of rivets 4, 4, or other desired means. Both the bar and the piece A should extend entirely across the screen to 55 be fitted with the trap, and the screen wire cut just beyond the line of attachment.

Extending upwardly and toward the outside of the screen to be fitted, the piece A is bent longitudinally at 5 at about a thirty-five degree angle to the vertical, and at its 60 upper edge may be turned back upwardly again, at 6.

The piece B has likewise a straight portion 7 which extends across the screen and is secured by suitable rivets 8 to the straight 65 bar 2 on the other side of the screen wire. The piece B extends downwardly from its point of attachment and is bent around on itself to form a longitudinal channel 9 opening upwardly on the outside of the 70 screen. As in the first case, the wire will be cut away just beyond the line of attachment.

Another alternative form of my invention comprises but one piece (Figure 3) of 75 sheet metal. In this form, which is the least expensive form, a strip of sheet metal is rolled lengthwise to form (beginning at the top) an overlapping fold 11, a straight portion 12, and a curve 13. From the curve 80 13 the metal extends at right angle to the portion 12, thence is bent back in a general slant 14, until in the plane of the portion 12, where another overlapping fold 15 is made. After the rolling, the metal extending 85 at a right angle to the portion 12, is punched out, leaving narrow bridging strips 16, as in the first instance, which hold the two sections A and B of the device together, but leaves free the passageway 10 for the 90 exit of the flies.

In mounting this device in a new screen, it is planned to secure the portion B to the upper molding of the screen frame, and secure the upper edge of the screen wire to 95 the portion A, by bending the wire around the fold 15 and securing it in place with a suitable rivet 17.

If the device is to be mounted intermediate the ends of the frame, then the fold 11 100 will be employed as in the case of the fold 15, to secure the wire gauze, employing rivets 18. This method of mounting is preferred for old screens, but may be used for new screens as well if desired.

It can be readily observed that the cheapness of manufacture and readiness and simplicity of installation recommends this form over my first described form of device, this first form being chiefly of value for superior 110 strength and durability.

The pieces above described should be

placed in the screen so that an outwardly and upwardly sloping passageway 10 (Figures 2 and 3) extends across the screen, with the upper edges of the pieces A and B at 5 the mouth of the passage on the outside on approximately a level. The width should not be more than enough for a large fly to pass through easily. Moreover the placing of these edges on a level prevents a fly from 10 alighting on one of the inner walls of the passage.

It should be noted that the fly moving down the screen on the outside will rarely get 15 as far into the channel 9 as the large fly at D is shown. Before the fly reaches this position, he will cease to walk and will fly. The edges of the pieces A and B on the outside of the screen are too narrow for the fly 20 to stand or walk on, and the fly walking up the outside of the piece A when it comes to 25 the edge thereof will fly or jump across the gap rather than walk down the passage 10. Coming from either direction the fly will step or jump across this opening, an additional reason for this being that he cannot 30 see light through the passage.

On the inside, however, the fly walking up the screen, will see the light up through the 35 passage and will be attracted to walk out 40 through it. Once it gets outside, it cannot get back in again without actually flying direct into the passage, which it will rarely do.

A fly will sometimes jump or fly across the 35 space across the passage 10 when it comes at the trap from above, but here again, it will usually walk part way around until it sees the open space of the passageway and the light shining through, when it will usually 45 walk back up the passage and outside of the room.

To facilitate the mounting of these devices in a screen that is already wired, their design has been specially adapted. The simplest method of mounting the device in a 45 screen is to lay the pieces against the face of the wire and secure them in place after which the wire is cut away. To do this

necessitates a flat surface to present to the screen wire, and a protruding central portion would require that the wire be cut before both edges of the device could be secured in place.

Accordingly it will be noted that a straight line drawn on the outside, for example, of the portions 3 and 7 of Figure 2 will not be 55 interfered with by the protruding of the portions 6 and 9.

I have shown in Figure 4 another modification in which the inner side of the device is the flat side, and this device in Figure 4 is 60 intended for mounting on the outside of the screen. In connection with the form shown in Figure 4, I have shown tongues 20, stamped out of the metal of the sections A and B, as indicated at 19, 19, Figure 4. 65

In each of my modifications, the principle is that of an outwardly and upwardly sloping passageway for the flies protected on the outside against flies entering by means of the 70 positioning of the edges of the side walls of the passageway.

Having thus described my invention, what I claim as new and desire to secure by Letters Patent, is:—

In combination with a fly screen, a trap 75 for insects comprising a metallic strip composed of a lower and an upper piece to extend across the screen intermediate the top and bottom cross bars of the frame, means for securing the strip to the screen, said 80 pieces being bent to form an upwardly and outwardly sloping passageway running from the inside of the screen to the outside, and having bridging strips terminating on approximately an horizontal plane on the outside of the screen, with the upper piece 85 curved in a gradual curve inwardly and outwardly and then upwardly and the lower piece upwardly on an outward slant, to provide an effective pathway for insects over 90 both pieces of the trap from the inside to the outside of the screen.

GEORGE W. MOSHER.
